UNITED STATES PATENT OFFICE.

JOHN H. PROFFITT, OF FRESNO, CALIFORNIA, ASSIGNOR OF ONE-HALF TO REED HAAS,
OF LOS ANGELES, CALIFORNIA.

AUXILIARY AIR INTAKE FOR INTERNAL-COMBUSTION ENGINES.

Application filed October 13, 1920. Serial No. 416,762.

To all whom it may concern:

Be it known that I, JOHN H. PROFFITT, a citizen of the United States, and resident of Fresno, county of Fresno, State of California, have invented a new and useful Auxiliary Air Intake for Internal-Combustion Engines, of which the following is a specification.

My invention relates in general to charge forming devices for internal combustion engines and has reference more particularly to an improved auxiliary air intake which is adapted to be used in association with the engine intake and manually controlled from a point, for instance, adjacent the seat of the driver, preferably from the instrument board of an automobile, for controlling the effective port area of the auxiliary intake so as to vary at will the additional air supply.

One of the important features of the invention resides in so constructing the auxiliary air intake that hot air may be used, to which end it is proposed, in so far as concerns the preferred embodiment of the invention, utilizing the heat of the exhaust pipe for heating the air supplied to the device.

Another important feature of the invention resides in so constructing the device that it may be attached to the intake of an internal combustion engine without departing from the original construction of the intake or otherwise materially changing the intake to accommodate the device. In this way the device may be applied to any kind of conventional type of engine now used.

Another important feature resides in the simplicity of construction of the device, which will enable the same to be manufactured at a modest cost and applied without skill or special tools. With these and further features this invention possesses, which will be more particularly pointed out as the description proceeds, the details employed as an illustrative embodiment will be described with reference to the accompanying drawing, in which Figure 1 is a side elevation of a conventional type of internal combustion engine illustrating the application of the invention; Figure 2 is a plan view partly in section of the device, and Figure 3 is a cross section through the device.

Referring now to the drawing in detail, A represents an ordinary type of engine

which is used either in motor vehicles of either the pleasure or commercial type, or it may be a stationary or marine engine. This is of minor importance in so far as concerns the salient features of the invention.

The engine A is provided with the customary intake manifold B which includes an intake pipe having the usual flanges C and D, and the section E which is connected to the charge forming device or carburetor, not shown.

The device is so constructed that it may be applied between the confronting flanges C and D to offer a convenient manner of equipping the engine with the device. With this end in view, the major part of the device comprises a plate (5) which is of a desirable thickness and shaped substantially the same as the flanges C and D. Openings (6) and (7) are arranged in the relatively narrow opposite ends of the device, through which the customary bolts of the flanges C and D are adapted to pass in clamping the plate between the flanges. If desirable, suitable gaskets may be used to effect a leak-proof joint. Arranged at one side of the plate (5) and preferably as an integral part thereof, is tubing (8) which represents the manifold for the device. At one end of the tubing (8) is arranged a connection (9) for the air supply tubing or piping which establishes a communication between the tubing (8) and the point around the exhaust pipe of the engine, not shown. The opposite end of the tubing (8) is closed by a collar (10) with the exception of a relatively small axial opening through which the rod or wire (11) of the piston (12) passes. The end of this rod or wire (11) may extend to any convenient location such, for instance, as the instrument board of the motor vehicle, so that it may be manipulated to slide the piston (12) longitudinally of the tubing (8). The wire is connected to the piston by being received in a central bore of the piston and fixed therein by a set screw (13) which is counter-sunk as shown so as not to interfere with the free movement of the piston within the tubing.

The central part of the plate (5) for a radius substantially that of the diameter of the opening in the intake pipe of the engine, is perforated as at (13^a) so that when the plate is inserted in the intake it will intercept the carburetted charge passing

there-through so that the perforations will permit the same to pass through the pipe into the working cylinders of the engine.

Arranged transversely of the perforations 5 (13^a) and extending within the thickness of the plate (5) and communicating with the tubing (8) are a series of ducts (14). These ducts establish a connection between the perforations (13^a) and the tubing or manifold 10 fold (8) so that the heated air being admitted to the tubing or manifold as above mentioned will be supplied through the perforations (13^a), where it will mingle with the incoming carburetted charge for varying the mixture thereof.

To regulate the amount of auxiliary air supplied through this series of ducts, the piston (12) may be moved longitudinally of the tubing (8) across the ends of the 20 ducts (14) to control the effective port area of the same; for instance, by closing several of the openings and leaving only two of them active, less air will be admitted through the perforations (13^a) than 25 if all of the ducts were left open as shown in Figure 2.

Instead of taking the heated air off the exhaust piping, it is of course obvious that any other heating medium may be resorted 30 to; in fact even though the heated air is desirable, it will not be departing from the spirit of the invention to eliminate the heating arrangement and to introduce the air directly into the end of the tubing (8).

35 I claim:

1. An auxiliary air intake for internal combustion engines, embodying in its construction a perforated plate adapted to be fitted to the intake of the engine to intercept the carburetted charge passing there-through, an air supply communicating with said perforations transversely of the plate, through ducts arranged transversely of the plate for establishing a communication between the perforations and an air supply.

2. An auxiliary air intake for internal combustion engines, comprising a perforated plate adapted to be fitted to the intake of the engine to intercept the carburetted charge passing there-through, transverse ducts communicating with the perforations and an air supply, and means for controlling the effective port area of said ducts.

3. An auxiliary air intake for internal combustion engines, comprising a perforated plate adapted to be fitted to the intake of the engine to intercept the carburetted charge passing there-through, transverse ducts communicating with the perforations and an air supply, and means for controlling the effective port area of said ducts comprising a valve adapted to be moved across the ends of the ducts.

4. An auxiliary air intake for internal combustion engines, comprising a perforated plate adapted to be fitted between the confronting existing flanges of the engine intake and adapted to intercept the carburetted charge passing there-through, said plate embodying in its construction a manifold tubing and ducts arranged in the thickness of the plate transversely to the said perforations and communicating at one end with the manifold tubing and terminating in communication with the perforations of the plate, and a valve slidably mounted in said manifold tubing adapted to be moved across the ends of the ducts for controlling the effective port area of the same.

5. An auxiliary air intake for internal combustion engines as set forth in claim 4, and in which the manifold tubing is made at one side of the plate, with one end thereof communicating with a source of heated air supply and in which the said valve for controlling the effective port area of the ducts has a manipulating means projecting through the opposite end of the manifold tubing.

JOHN H. PROFFITT.
